UNITED STATES PATENT OFFICE.

EDWARD D. HUXFORD, OF CHEROKEE, IOWA.

CHECK-PRINTING MACHINE.

1,030,889.

Specification of Letters Patent. Patented July 2, 1912.

Application filed April 8, 1910. Serial No. 554,229.

To all whom it may concern:

Be it known that I, EDWARD D. HUXFORD, a citizen of the United States, residing at Cherokee, in the county of Cherokee and 5 State of Iowa, have invented certain new and useful Improvements in Check-Printing Machines, of which the following is a specification.

This invention relates to an improved 10 check printing machine, and has for its principal object to provide a machine for the purpose described, in which the value of the check in both figures and words is printed in one operation.

15 Another object of this invention is to provide a machine of the character described which will simultaneously with the printing operation, work into the fiber, a non-erasable and permanent ink, thus preventing the 20 value of the check from being altered in any manner without detection.

A still further object of this invention is to provide such a machine of comparatively few parts and it is therefore simple in construction and cheap to manufacture.

With these and other objects in view, the invention comprises the novel combination of parts hereinafter more fully described and pointed out in the appended claims, it 30 being understood that various changes in size, proportion and minor details of construction within the scope of the claims can be made without departing from or sacrificing any of the advantages of the invention.

In the drawings:—Figure 1 is an end view of the machine; Fig. 2 is a front elevation of the machine; Fig. 3 is a diagrammatic view of the key-board, Fig. 4 is a perspective view of one pair of type segments, Fig. 5 is a top plan view of the guide-plate, and Fig. 6 is a side elevation of a key.

Like reference numerals designate corresponding parts in all the figures of the 45 drawings.

Referring to the drawing, the invention comprises a base 5, and a rear wall 6. Brackets 7 7 are respectively arranged at each end of the base, and are adapted to 50 form a support for a fixed longitudinal shaft 8. A plurality of pairs of type-carrying segments are rotatively mounted on the said shaft, and each pair of segments comprises a "number segment" 9 and a "word segment" 10.

The "number segment" is preferably

formed of the skeleton type, that is, it consists of radial arms 9^a 9^a, which are united at their outer ends by a concentric arm 9^b. The jointure of the two arms is provided with a bearing 9^c which is rotatively mounted to form a support for a plurality of radially extending "numerically arranged number" types 9^d, said types consisting of the numbers 0, 1, 2, 3, 4, 5, 6, 7, 8, 9, or the 65 like. A rearwardly extending curved arm 9^e is arranged integral with the rear radial arm 9^a.

The "word segment" is constructed in an almost identical manner as the "number segment". It comprises a pair of skeleton members, each member comprising radial arms 10^a 10^a which are united at their outer ends by a concentric arm 10^b. The jointure of the two arms of each member is provided with alined bearings 10^c which are rotatively mounted on the shaft 8. These members are spaced apart a certain distance, and the concentric arms 10^b form supports for a plurality of "word" types 10^d, said types 80 consisting of the words, One— Two— Three— etc., or One hundred— Two hundred— Three hundred— etc., and so on, including the thousands, millions, or whatever numbers are deemed necessary. A rearwardly extending curved arm 10^e, similar to the curved arm 9^e of the "number segment", is arranged integral with one of the rear radial arms 10^a, and in alinement with the said arm 9^a. A forwardly extending curved arm 11 is forced integral with the concentric arm 10^b, and has an angular end 11^a.

A rod 10^x connects the two arms 9^e and 10^e, and therefore the two segments 9 and 10, revolve in unison on the shaft 8.

Levers 12 12 are respectively secured at each end of the shaft 8 to rotate therewith, and are provided with alined openings 13 13 near their ends for the reception of a connecting rod 14. A plurality of coiled springs 100 15 each have one end connected to the rod 14 and the other end to one pair of segments. Furthermore, levers 12 12 are provided with alined openings 12^a 12^a near the shaft for the reception of a connecting rod 12^b, the purpose of said rod being to force the segments back to their normal position after each movement of the handle, that is, this rod 12^b comes in contact with the radial arms 10^a and 9^a when the handle is released 110 and forces them back to their normal position.

To the front edge of the base 5, is connected a front vertical wall 16 which terminates rearwardly in an upwardly inclined top casing 17. The top casing then extends 5 upwardly and rearwardly and is bent to form a curved portion 18, against which, on the underside, the segments 9 and 10 move, as will hereinafter be fully described. Projecting from the base 5, and arranged substantially underneath the juncture of the top 17 and the curved portion 18 thereof, is a longitudinal support 19 which is cut out on its rear face as shown so as to form a continuation of the curve of the top portion 15 18, both of said curves being concentric with the shaft 8.

A plurality of parallel transverse rows of spaced keys 21 project through the inclined top casing 17, and the keys of each row are 20 each pivotally supported by a rocker-arm 22 that is pivoted to the key-stem 23 and to an angle-iron strip 24, said strip 24 being secured to the underside of the top casing 17. Arranged directly below each row of 25 the keys and parallel with the top casing is a transverse support 25 which is secured at one end to the front wall 16, and at the other end to the top of the support 19. A guide plate 25^a is arranged thereon, and 30 adapted to be moved longitudinally. The said guide plate is provided with an elongated longitudinal opening 25^b at either end and a screw 25^c or other suitable means is arranged to pass through the said opening 35 25^b and into the support 25. A plurality of spaced elongated openings 25^d are formed in the said guide plate and are respectively spaced apart a distance equal to the distance between the keys arranged thereabove. The 40 lower end of each key-stem is rearwardly curved as shown by 26, and said end is adapted to enter the corresponding opening 25^d of the guide plate. It will therefore be observed that when one of the keys is 45 pressed the rearwardly curved end of the key-stem will engage the rear edge of the contiguous opening 25^d and thereby cause the guide plate to be moved rearwardly. This movement of the guide plate causes all 50 of the other openings 25^d of the plate to be thrown out of register with their corresponding keys and thereby prevent the depression of all other keys in that particular row. A coiled spring 27 is connected at one end to 55 the key-stem and at the other end to the rocker-arm for a purpose as will hereinafter appear. Pivottally connected to the other end of each rocker-arm is link member 28 having its free end underbeveled as shown 60 by 29. These link members are arranged horizontally and are slidably mounted in the support 19. Thus it will be observed, that each transverse row of keys has a corresponding vertical row of link members. 65 Normally, the said link members do not

project through the support 19, but when the keys are depressed, the corresponding free ends of the link members will project beyond the rear curved face 20 of the support. Furthermore, it will be observed that 70 for each row of keys there will be a corresponding pair of segments, excepting that the keys numbered 11 to 19 govern the segment (having thereon the words from "Ten dollars" to "Ninety dollars") after said segment is revolved in a forward movement beyond the printing point of the word "Ninety dollars." In explanation of this, it will be understood that there is a pair of 75 segments for the divisions "One cent" to "Nine cents;" a pair for "Ten cents" to "Ninety cents;" a pair for "One dollar" to "Nine dollars;" a pair for "Ten dollars" to "Ninety dollars," etc., and it will thus be evident that the words "Eleven dollars," "Twelve dollars" and up to "Nineteen dollars" could not be written without 80 additional mechanical means. This is accomplished by having concentric arms 10^b extended so that in addition to the words "Ten dollars" to "Ninety dollars" thereon, there is also the words "Eleven dollars" to "Nineteen dollars" thereon and the corresponding figures on the numeral segments attached thereto. The rotation of this 85 segment, after it is past the printing point of "Ninety dollars," is governed by the keys having thereon the numbers 11, 12, 13, etc., to 19, in the following manner:—This segment has two forwardly extending arms 11 90 one the same length as the other segments and the other of such a length that the segment is permitted to rotate beyond the printing point of the word "Ninety dollars" before the length member of the keys marked "11" to "19" inclusive would arrest and govern its rotation. It will be noted in this connection that it is not necessary to have this combination to all forwardly extending arms on the other segments, as this machine writes "One thousand, one hundred," etc., and not eleven hundred, etc.

Secured to one end of the shaft 8 to rotate therewith, is an operating handle 30, and the handle is connected to an extension 31 of the bracket 7 by means of a coiled spring 32 and is thus normally held in an inoperative position. Also keyed to the shaft at opposite ends thereof, are arms 33. The free ends of the arms 33 terminate short of the support 19, and are each provided on the underside with a shoulder 34. A dog 35 is arranged between the two arms and is pivotally connected thereto. The said dog normally abuts against the shoulder 34 preventing the downward movement of the dog, but permitting an upward movement thereof. Also keyed to each end of the shaft to move therewith upon movement of the handle, are short arms 36 36. Pivoted to the 105 110 115 120 125 130

top of the casing, are arms 37 37, the free ends of which are connected to a platen 38. Pivoted to the free ends of the short arms 36 36, are upwardly extending links 39 39, the upper ends of which being each provided with an elongated slot 40. The platen is arranged between the said arms, and is connected thereto by means of screws 41 41, which pass through the said slots 40 40. A spiral spring 42, or other resilient means, is arranged within each slot to bear against the said screw 41 and thereby cushion the platen. A tensioning screw 43 is arranged in the end of each arm to adjust the said spring as will be readily understood. The screws 43 carry collars 43^a against which the upper ends of the springs 42 bear.

Supported by the rear wall 6, and contiguous to the segments is an ink pad 44 and roller 45, which inks the type as the same comes in contact therewith.

Secured to the brackets 19^a on the rear face of the support 19, below the link members, is a pivoted L-shaped longitudinal stop 20^a. One leg 20^b of the stop rests normally against the support, while the other leg 20^c projects into the path of movement of the forwardly extending arms 11 of the "word segments".

In operation when certain keys are depressed, the corresponding link members 28 are projected beyond the support 19 and into the path of movement of the forwardly projecting arm 11 of the "number segment". As a result, upon the movement of the handle against the action of the spring 32, the levers 12 connecting rod 14, the springs 15, and consequently the segments are rotated upon the shaft 8. As the segments rotate, the forwardly projecting arm of some of the segments will abut against the projecting free ends 29 of the link members 28 and will of course be stopped while the other segments will pass out of alignment with the other segments. As will be readily understood, those segments which have been stopped, have a particular type corresponding to the key depressed, in position to be employed for stamping a check. Simultaneously with this movement, the segments contact with the ink roller, and thereby ink the type thereof, and immediately afterward, the short arms 36 36 cause the links 39 39 to move downward, taking with them the platen 38. Upon the extreme movement of the handle, the platen is forced against a check (it being understood that a check has been properly positioned), and the check against the type of the segments which have been previously stopped. Upon the return movement, or release of the handle, the arms 33 are elevated, and the dogs 35 abutting against the shoulders 34, will engage the beveled ends 29 of the link members 28 and cause the

same to be forced back to their normal position, and the platen will, of course, be likewise shifted to its normal position.

It will be observed that when the handle is moved to the greatest position, the arms 11 of the "word segment" will engage the legs 20^c of the stops 20^a and thereby limit the movement of the said segments. Upon the return of the handle to its normal position, the dogs 35 of the arms 33 will trip the stops 20^a and permit the said arms 33 to pass.

What I claim is:—

1. A printing machine, comprising in combination, a plurality of rotatable segments, means for rotating said segments, and having a resilient connection therewith, and selective means for obstructing certain of said segments against the pull of said rotating means, said selective means comprising a plurality of keys, and longitudinally slid able members linked to said keys to be moved into the paths of movement of said segments.

2. A printing machine, comprising in combination, a plurality of rotatable segments, means for rotating said segments and having a resilient connection therewith, and selective means for obstructing certain of said segments against the pull of said rotating means, said selective means comprising a plurality of keys arranged in groups corresponding to said segments, means to prevent actuation of the remaining keys of a group when one key is depressed, and slideable members linked to said keys to be moved into the paths of movement of said segments when the keys are depressed.

3. A printing machine, comprising in combination, a plurality of rotatable segments, means for rotating said segments and having a resilient connection therewith, and selective means for obstructing certain of said segments against the pull of said rotating means, said segments comprising yoked pairs of arcuate printing surfaces adapted to be grouped for printing.

4. A printing machine, comprising in combination, a plurality of rotatable segments, means for rotating said segments and having a resilient connection therewith, and selective means for obstructing certain of said segments against the pull of said rotating means, said segments comprising yoked pairs of arcuate printing surfaces and means to lock each segment against forward movement.

5. A printing machine comprising a rotatable shaft having an operating handle connected thereto, a plurality of type segments rotatively mounted on said shaft, a plurality of keys, a member associated with each key adapted to be projected into the path of movement of a segment upon the depression of said key, a platen, means con-

neeted to the shaft for rotating all of the segments, means connecting the shaft and platen for pressing the latter against the segments, which have been stopped by the 5 said projecting members, both of said means being operated upon the forward movement of the handle, and means associated with the shaft for returning the projecting members to their normal position upon the re- 10 turn movement of the said handle.

6. A printing machine comprising a rotatable shaft, a plurality of type segments rotatively mounted thereon, spaced arms secured to the shaft to rotate therewith, a 15 rod connecting the arms, coiled springs re-

spectively connecting the rod and each segment, means for stopping the rotation of some of the segments at a predetermined position, a platen arranged in close proximity to the segments, and connected to the 20 shaft, and operating means connected to the shaft for rotating all of the segments and for pressing the platen against those segments which have been stopped.

In testimony whereof I affix my signature in presence of two witnesses. 25

EDWARD D. HUXFORD.
